UNITED STATES PATENT OFFICE

LELAND G. KNAPP, OF CHICAGO, ILLINOIS, ASSIGNOR TO MONTGOMERY WARD & CO., INC., OF CHICAGO, ILLINOIS, A CORPORATION OF ILLINOIS

WASHING MACHINE

Application filed July 16, 1927. Serial No. 206,213.

This invention relates to power-driven washing machines and it has particular relation to machines wherein a washing vessel is mounted in a frame work or cabinet to be 5 intermittently driven by means of a motor mechanism mounted on said frame work.

Among the objects of the invention is a machine of the foregoing type characterized by a novel clutch mechanism for transmitting the movement of the motor to the washing vessel and the cooperative relationship of said clutch mechanism with the parts of the machine whereby a simple, efficient and economic structure is obtained.

15 The invention will be best understood from the following description of exemplifications thereof, reference being had to the accompanying drawings, wherein

20 Fig. 1 is an elevational view of a washing machine embodying the invention, with the front wall cut off along the line I—I in Fig. 2;

25 Fig. 2 is a horizontal sectional view through the machine along the line II—II in Fig. 1;

Fig. 3 is a vertical sectional view of the upper portion of the machine along the line III—III in Fig. 2;

30 Fig. 4 is a view similar to Fig. 1 of a modification of the invention;

Fig. 5 is a horizontal sectional view through the modification along the line V—V in Fig. 4;

35 Fig. 6 is a sectional view of a portion of said machine along the line VI—VI in Fig. 5; and

Fig. 7 is a horizontal sectional view of the clutch mechanism along the line VII—VII in Fig. 4.

40 The present invention is the result of a development directed to the provision of a simple combination of a power driving mechanism and washing vessel support suitable for use in washing machines operating either on the oscillating principle or on the reversing-cylinder principle, with a view to housing the mechanisms of the two kinds of machines in a cabinet of the same size and employing a maximum of interchangeable parts in the mechanisms of the two machines,

while making such mechanism simple, efficient, readily accessible and reliable.

In the washing machine of the oscillating type a tub in the form of a flattened cylinder is given a limited oscillatory motion, 55 imparting thereby to the washing fluid in the interior of the tub a figure 8 movement which forces a stream of water through the fabrics that are to be cleaned. In the reversing-cylinder machine a perforated cylinder 60 in which the fabrics that are to be washed are placed is given a rotary movement within a tub containing the cleaning fluid, the cylinder rotating alternately first in one direction and then in another direction, or, in some cases, only in one direction. 65

My invention provides a novel mounting or support for the movable washing vessel of either of the foregoing types of machines, combined with a simple clutch mechanism 70 for imparting the required motion to the vessel. The mounting and clutch mechanism are such as to permit utilization of the same framework or cabinet for either type of machine. 75

An exemplification of the invention as applied to a machine of the oscillatory type is shown in Figs. 1 to 3. A horizontally-mounted flattened cylindrical washing tub 1 is arranged for oscillatory movement 80 around the horizontal axis 2 thereof. The tub is held in a cradle comprising a rear-end casting 4 and a front-end casting 5 secured to the end walls of the tub and joined to each other by suitable stiffening members 85 6 supporting the bottom of the tub.

The tub is mounted in a square washing cabinet comprising a framework of angle iron posts 11 that are stiffened by suitable cross members 12 extending between the posts. Metal sheets 13 extending between the posts 11 and welded thereto constitute the walls of the cabinet and serve to additionally stiffen the same. In order to give to the tub 1 the oscillatory or rocking movement referred to above, the rear and front castings 4 and 5 of the cradle provide a trunnion support along the horizontal axis 95 of the tub. The rear trunnion support comprises a section 14 journaled in a suitable 100

bearing casting 15 secured to the rear wall of the cabinet. The front trunnion support comprises a cylindrical forward extension 16, on the front casting 5 of the cradle, fitting over a shaft 17 of a clutch mechanism 18 through which movement is imparted to said tub.

The clutch mechanism 18 comprises a cast, box-like clutch housing having a front wall 10 or traverse 21 extending between, and secured to, the two front posts of the cabinet as by bolts 19, adding additional stiffness to the structure; and a rear wall 22 that extends in spaced relationship from said front wall 15 and is stiffened thereagainst by means of stiffening ribs 23. A free space is thus left between the front and rear walls of said housing.

Extending transversely through the center 20 of the clutch housing is the aforementioned shaft 17 having an inner turned-down portion 25, the end of which fits into the cylindrical extension 16 of the tub to support the same for rotary or oscillatory movement. 25 The front portion of the shaft 17 is journaled in a bearing extension 26 in the outer wall of the clutch housing. A latch 27, pivoted at 28 on the front wall of the housing, is arranged to engage a circular slot 29 in 30 the outer shaft end so as to lock the same against axial movement when the machine is in an assembled condition. The portion of the shaft projects in front of the cabinet and forms a knob 30.

35 The inner portion 25 of the driving shaft is journaled in a cylindrical bearing shell 31 that is inserted through a suitable opening in the inner wall 22 of the clutch housing and secured thereto by a nut 32 threaded over said bearing shell on the outer side of said wall, said shell having a shoulder 33 bearing against the inner side of the wall. A metal sheet constituting a partition 35 separating the space within the cabinet into 40 a compartment around the tub and a compartment housing the clutch and power mechanism is held in place by the nut 32.

Mounted on the shaft 25 within the free space between the outer wall 21 and inner 50 wall 22 of the clutch housing there is a driving clutch member 41 and a driven clutch member 42 for determinedly transmitting oscillatory or rotary movement to the tub. The driving clutch member has the form of 55 a flat disk provided with a central hub portion 43 surrounding the shaft 25 and arranged to freely rotate thereon. A plurality of teeth or driving projections 44 extends from said disk toward the driven clutch member. The driven clutch member 42 has 60 also the form of a disk disposed opposite the disk of the driving clutch member 41 and is also provided with a hub member 46 fitting the turned-down rear portion 25 of 65 the shaft and is arranged for free axial

sliding movement on said shaft portion. A key 47 locks said driven shaft member to the shaft against rotary movement. The disk of the driven clutch member 42 is provided with indentations or cut-outs 48 constituting a counterpart of the driving projections 44 of the driven clutch member so that a driving engagement between said two clutch members may be effected by sliding the driven clutch member on the shaft until 70 the projections 44 come into the interdental spaces 48 of the driven clutch member. By sliding the driven clutch member 42 back so as to release said engagement, the driving connection is interrupted. The driving 75 clutch member thus constitutes the male part of the clutch while the driven part of the clutch member constitutes the female part thereof.

As seen in the drawings, the outer diameter of the driving clutch member 41 is somewhat larger than the diameter of the driven clutch member 42, the outer portion of said driving clutch member constituting a shoulder adapted to bear against inwardly projecting portions 51 of the rear wall of the clutch housing to prevent axial movement of the driving clutch member on the shaft 17.

The female clutch member 42 is moved in or out of engagement with the male clutch member by means of an actuating lever 55 having a pair of fingers 56 fitting into a reduced neck portion on the hub 46 of said female clutch member, the lever being pivoted at an intermediate portion thereof on a cap bolt 57 screwed into the left-hand side wall of the clutch housing. A handle arm 59 that is secured to the free end of the actuating lever 55 by means of a draw bolt 60 serves to extend said lever outside of the cabinet to permit manipulation during the operation of the machine.

In the wall portion of the cabinet through which said handle arm 59 extends there are provided two short vertical slots 61 interconnected by a transverse horizontal slot to permit movement of the actuating lever from the inner to the outer position, and vice versa. The actuating lever and the extension thereof have a certain amount of resiliency to permit slight bending thereof in vertical direction and are so biased as to drop into the vertical slots 61. In order to bring the lever from one position to another, the handle is slightly lifted upward to bring it to the height of the transverse slot, then moved along said transverse slot to the other position and permitted to drop into the other vertical slot.

To take up any variations in the relative location of the slots 61 and the mounting of the lever 55, the handle 59 and lever 55 may be relatively adjusted, loosening the bolt 60 and then tightening the same in the 130

adjusted position, radial corrugations 64 in the cooperating surfaces on the lever 55 and handle 59 locking said two members against movement with respect to each other.

5 The driven clutch member 42 has a downwardly-extending rearwardly-bent arm 71 fitting into a vertical slot 72 in the front-end casting 5 on the tub cradle to provide a positive driving connection between said clutch member and the tub. With the foregoing arrangement the inner end of the driving shaft 25 constitutes only the central support of the tub while the driving torque for oscillating the tub is applied through 10 said driving arm 71 of the clutch, the shaft 17, the female clutch member 42 and the tub oscillating in unison.

This arrangement provides a very firm support and driving connection for the tub while permitting ready removal thereof from the cabinet. If such removal is desired, the latch 28 is lifted and the shaft 17 is pulled toward the front by means of the knob portion 30 until the inner shaft end clears the cylindrical extension 16 on the front casting 5 of the tub cradle. The tub 1 may thereupon be lifted upward and removed from the cabinet, the supporting journaling portion for the rear shaft member 14 being open on the top. In order to prevent the shaft 17 from being pulled out fully from the clutch housing, a set screw 74 is provided on the reduced shaft portion 26, fitting into a keyway in the hub portion of the female clutch member 42 opposite the driving key 47, said screw being adapted to bear against the inner edge of the driving clutch disk 41 when said shaft is pulled to the front.

15 In order to impart to the tub the aforementioned oscillatory movement, the driving clutch member 41 is provided with a driving arm 81 which is engaged by the upper end of a pitman rod 82 leading to the motor or power mechanism 83 that is mounted in the bottom of the cabinet. The motor mechanism comprises an electrical motor 84 driving through a V-shaped belt 85 and a pulley 86 which in turn imparts movement to a train of gears 87 to 91. From one of said gears rotary movement is transmitted to a vertical wringer shaft 92 mounted adjacent to a side wall of the cabinet and having at its top a coupling box 93 into which a wringer of familiar construction may be inserted. This part of the machine does not constitute a subject of the present invention and is therefore not further described.

20 From another of said gears rotary motion is imparted to a crank arm 95 provided with a wrist pin 96 engaging the lower end of the pitman 82, thereby translating the rotary movement imparted to the gears by the electric motor 84 into a reciprocating movement of the pitman. The up-and-down

reciprocating movement of the pitman in turn imparts oscillatory movement to the driving clutch member 41. When the two clutch members are in engagement, this oscillatory movement is imparted to the tub 1 through the medium of the driving arm 71. By placing the female clutch member out of engagement with the male clutch member, the oscillatory movement of the tub 1 is stopped. A holding spring 98 extending 25 between a roller 99 at the bottom of the cradle, and a supporting lug 100 at the bottom of the cabinet holds the tub normally in horizontal position.

In the oscillator machines of the foregoing type a quick reversal of the motion takes place, and accordingly a relatively large force is required to retard the large body that is in motion, and accelerate it in opposite direction. Accordingly, a relatively large power transmitting mechanism is required. The arrangement according to my invention secures the required torque transmitting connection with a minimum of parts and in a limited space. The two 30 clutch members may be made relatively large and in the preferred arrangement the two clutch disks are about five inches in diameter. The utilization of the clutch mechanism as one trunnion support for the tub greatly simplifies the construction of the machine and the mounting of the power transmitting parts thereof, the clutch housing constituting what may be termed a bracket for supporting the tub on a side wall 35 of the cabinet. The clutch housing with its front wall extending between the two up-standing angle iron supports of the cabinet adds additional stiffness to the entire structure in the portion which has to transmit the greatest forces. A strut 102 extending 40 between the gear train mechanism 87 to 91 and the clutch housing serves to brace the two parts with respect to each other, and further reduces the stresses within the framework 45 of the cabinet.

The construction described above permits adaptation of the same cabinet with substantially the same power driving mechanism for washing machines of various types, and in Figs. 4 to 7 I have shown a reversible-cylinder washing machine arranged to be mounted within the same cabinet and utilizing substantially the same driving mechanism and clutch support as the oscillator machine of Figs. 1 to 3. The reversible-cylinder washing machine comprises a semi-cylindrical tub or trough 110 supported in a cabinet of the same construction as that described above.

125 Mounted horizontally within said trough is a perforated washing cylinder 111 in which the fabrics that are to be washed are placed. At the rear end, the cylinder is provided with an end casting 112 having an 130

axially extending journal 113 fitting into a corresponding bearing 114 secured to the rear wall of the tub structure. The forward end of the cylinder carries an end casting 115 provided with a forwardly extending boss 116 that has in its center a broached hole 117. Into this broached hole fits the inner end of a driving shaft 118 that constitutes the other journal of the washing cylinder 111. Said driving shaft 118 is in every respect identical with the driving shaft 17 of the mechanism in Figs. 1 to 3, except that the inner end thereof has milled flats to fit into the broached hole of the extension 116 in the front casting of the cylinder, thus securing a driving engagement between said two parts. The driving shaft 118 is supported in a clutch housing 119 of the same construction and shape as that of the oscillating washing machine described above, all the parts of the two clutch mechanisms being exactly alike, except as specifically referred to hereinabove.

The female or driven clutch member 120 differs from that in Figs. 1 to 3 in that it does not have the downwardly extending driving arm 71, the motion being, in the present instance, transmitted through the locking engagement between the rear end 30 of the driving shaft and the cooperating broached hole in the front extension 116 on the cylinder. The driving clutch member 121 differs from that shown in Figs. 1 to 3 in that it does not have the driving arm 35 81 but is provided instead with a pinion 123 surrounding the hub portion of said clutch member. Motion is imparted to the driving clutch member through a rack 125 engaging said pinion 123, the lower end of 40 said rack being journaled on a wrist pin 126 of a gear wheel 127, constituting a part of a gear train mechanism in a power plant 128 that is in its general layout and arrangement substantially like that of the 45 power plant in the oscillator machine of Figs. 1 to 3, except for changes in the gear ratio required to impart to the machine the speed best suited for the particular type of washing.

50 In order to secure proper engagement of the teeth of the rack and of the pinion, the back side of said rack bears against a roller 131 which is mounted on a swinging arm 132 that is pivotally secured to the front wall 55 of the clutch housing, said arm being pulled by means of a coil spring 133 toward said rack. The roller thus tends to press the rack teeth into engagement with the pinion teeth and resiliently prevents said rack 60 from receding back out of engagement with the pinion. In order to prevent the teeth of the rack from being pressed fully into the teeth of the pinion, in which case jamming and breakage of the teeth would occur, there is provided an adjustable stop

limiting the forward movement of said roller, said stop comprising a threaded bolt portion 135, Fig. 7, fitting into a threaded hole in the front wall of the clutch housing, the inner end of said bolt portion having an eccentric lug extension 136. The lug extension 136 of the bolt is arranged in front of the upper end of the swinging arm 132 and serves to limit the forward movement of said arm and said roller 131. By rotating the bolt, the forward limit of said movement may be readily adjusted, the preferred adjustment being such that the roller is prevented from pushing the rack closer than $\frac{1}{2}$ inch to complete engagement of the teeth. In order to prevent lateral movement of the rack, the back surface thereof is provided with a longitudinal groove 141 for receiving a radial ridge 142 in the roller 131 pressing against the back 80 of the rack.

As in the case of the oscillating machine, the washing cylinder may be readily removed from the tub by unlocking the driving shaft 118 and pulling out the rear driving end of said shaft from the broached opening in the extension 116 of the front casting of the cylinder, and thereupon lifting said cylinder from the tub.

In operation, the rack imparts to the driving clutch member 123 alternate rotary movements in one direction and the opposite direction, which movements are transmitted to the washing cylinder 111 by sliding the driven clutch member 120 forward into engagement with the driving clutch member.

In both exemplifications described hereinabove the washing machine member that is arranged for oscillatory or rotary movement has one of its trunnion supports combined with a clutch which thus constitutes one bracket support for journaling the removable washing machine member. The entire mechanism is very simple and permits ready disassembly of the parts while securing a structure of utmost rigidity and stiffness.

The invention is not limited to the specific arrangement and details of construction described hereinabove and it is, accordingly, desired that the appended claims be given a broad construction commensurate with the scope of the invention.

I claim:

1. In a power-driven washing machine comprising a supporting frame and washing member arranged within said frame for rotary movement around a horizontal axis, a clutch housing detachably secured as a unit to the exterior of said frame and constituting a part of the outer wall thereof, a gear element within said clutch housing and removable herewith as a unit, a drive element carried by said frame driving said gear element, a pair of co-operating clutch members in said housing for establishing 125

and breaking driving connection between said gear element and said washing member, and a shaft extending through said housing and supporting said clutch members, said 5 shaft constituting one trunnion support for said washing member and having limited longitudinal movement along the axis thereof to a position of disengagement from said washing member, and means for locking 10 said shaft in position of engagement with said member.

2. In a power-driven washing machine, a supporting frame, a washing member within said frame arranged to be driven to produce 15 washing action, a housing attached to the exterior of the frame substantially flush with the walls of said frame, and a drive element carried by said frame, said housing containing a clutch element operatively connected to said washing member to drive the same, a second clutch member for cooperation with said first clutch member, and a driven member driving said second clutch member and driven by said 20 drive element, whereby the housing and the elements it contains may be removed as a unit from said machine.

In testimony whereof I have hereunto 30 subscribed my name this 12 day of July,

LELAND G. KNAPP.
